UNITED STATES PATENT OFFICE

REGINALD FERGUSON, OF MONTREAL, QUEBEC, CANADA, ASSIGNOR, BY MESNE ASSIGNMENTS, TO SIMMONS COMPANY, OF NEW YORK, N. Y., A CORPORATION

BEDSPRING FABRIC

Application filed June 25, 1927, Serial No. 201,548, and in Canada March 17, 1927.

This invention relates broadly to improvements in bed-spring fabrics, or bed bottoms and more particularly to that type of bed-spring fabrics known as "cable springs" or 5 to equivalents thereof, and the object of the invention is to provide a structure of this type more firm than heretofore.

In cable springs or equivalent structures, such as those formed of longitudinal strands 10 each being a single wire, it is necessary to provide cross linkage between the longitudinal strands to hold the same against spreading and also to distribute among a number of adjacent strands a load placed on any 15 strand or group of strands. In some cases the linkage has been such as to displace the strands from their normal straight course between the end rails, thus producing diamond or honeycomb patterns with a view to 20 distributing load on any one strand diagonally across the spring to adjacent strands. For the most part, however, the strands have been straight and the links arranged in a staggered relation.

25 It is found that in springs constructed as aforesaid, there is not sufficient distribution of load through the spring and that the strands are not sufficiently mutually supporting, chiefly because the arrangements 30 used do not produce sufficient cross tension in the structure. Great difficulty has also been experienced in preventing cross linkage from creeping along the strands and leaving excessive lengths of the same without 35 lateral support, whereby the strands are easily forced apart and parts of the mattress enabled to enter between them.

The present invention aims to overcome 40 the disadvantages already noted by providing in a cable spring or equivalent structure, especially one with a transversely stiffened edge, a continuous cross linkage formed of interdigitating links enabling a 45 positive distribution of load entirely across the structure and at the same time tending to so distort the strands that link creepage is effectually prevented.

In the accompanying drawings which il- 50 lustrate two embodiments of the invention,

but to all the precise details of which the invention is not confined—

Fig. 1 is a plan view of a cable spring or 65 equivalent constructed according to the invention;

Fig. 2 is a fragmentary plan view, on a large scale, of one form of linkage;

Fig. 3 is a view similar to Fig. 2 showing another form of linkage; and

Fig. 4 is a cross-section on the line 4—4 60 of Fig. 3.

Referring more particularly to the drawings, 11 designates the end rails of a bed spring or bed frame between which are stretched the strands 12 of cable or wire forming the mattress support. Transversely stiff border members, such as flat bands of metal, are designated 13. The strands and border members are preferably connected to the end rails by a series of helical springs 14, as is usual. The strands 12 may be formed of a single continuous length of cable or wire, as shown, or may be separate. 70

The continuous cross linkage forming the subject of this invention is provided midway between the end rails, preferably in the form of several well spaced lines of tensioned linkage, designated 15 in Fig. 1. The continuous linkage is preferably not carried to the ends of the strands but is replaced toward the ends by ordinary staggered or non-continuous linkage, designated 16, or other suitable structure. It will be understood, however, that continuous linkage may be used throughout. 75

The continuous linkage embodies links of two sorts, designated 17 and 18 in Fig. 2 and arranged alternately. Each link 17 is in the form of a plate of appreciable width having at each end a pair of spaced arms 19 of length sufficient to be bent around adjacent strands, as clearly shown in Fig. 4. The links 18 are bent around the strands between the arms of the links 17, which are spaced apart somewhat more than the width of the links 18 to induce or tend to cause flexion of the strands between the links, as shown in exaggerated manner at 20.

In Fig. 3, there is shown another form 100

of continuous linkage differing from that already described only in that the links 18 are replaced by helical springs 21 which are hooked onto the strands between the arms of the links 17 in exactly the same manner as the links 18.

The maximum downward pressure to which the strands are subjected in use is usually applied about midway between the ends of the strands. When this pressure is applied to any strand or group of strands in a structure according to this invention, the strand or strands yield under the pressure. This yielding sets up tension in the continuous cross linkage and tends to draw every otherwise unloaded strand in the structure laterally out of its normal straight line. The lateral tension is also transmitted to the border members 18 which are relatively unyielding in the transverse direction. As a result of downward deflection of any strand in the structure, all the other strands are positively tensioned and resist the downward deflecting force. By the same means all the end helicals 14 of the structure share in supporting a load localized on any strand or group of strands and thus greatly relieve the end helicals of the directly loaded strand or strands. This feature is of paramount importance in the production of a sag-proof structure. In use, some strands are more persistently loaded than others and, if the load is not distributed, the end helicals of these strands become fatigued and permanently elongated producing an uncomfortable hollow in a mattress supported thereby. The continuous cross linkage accomplishes a distribution of local loading between all the end helicals of the structure which is not accomplished by staggered linkage or arrangement of the strands in a diamond or honeycomb pattern. The cross linkage including helical springs produces the same results as the rigid linkage but in varying degrees according to the stiffness of the spring links. The slight distortion of the strands or tendency thereto due to interdigitation of the links and a permanent tension in the cross linkage holds the links against creeping along the strands. If desired, the strands may be initially distorted as shown where they intersect the cross linkage to positively hold the links against creeping.

Having thus described my invention, what I claim is:

- 60 1. A bed-bottom fabric comprising longitudinal strands, a continuous jointed cross linkage between the strands located approximately midway between the ends of the strands, and non-continuous cross linkage of the strands between said continuous cross linkage and the ends of the strands.
- 65 2. A bed-bottom fabric comprising longi-

tudinal strands, a continuous jointed cross linkage between the strands including links of two sorts arranged alternately between and connecting adjacent strands, the links of one sort including at each end spaced arms hooked around the strands, and the links of the second sort hooking around the strands between the arms of the links of the first sort.

3. A structure according to claim 2, in which the links of the second sort are helical springs.

4. A structure according to claim 2, in which the links of the first sort are flat plates bifurcated at opposite ends.

5. A bed-bottom fabric comprising longitudinal strands, a continuous jointed cross linkage between the strands located approximately midway between the ends of the strands including links of two sorts arranged alternately, the links of one sort including at each end spaced arms hooked around the strands, and the links of the second sort hooking around the strands between the arms of the links of the first sort, and non-continuous cross linkage of the strands between said continuous cross linkage and the ends of the strands.

6. A bed-bottom fabric comprising longitudinal strands, a continuous jointed cross linkage between the strands including links of two sorts arranged alternately, the links of one sort being flat plates including at each end a pair of spaced arms hooked around the strands, and the links of the other sort being helical springs hooked at their ends around the strands between the arms of the links of the first sort.

7. A bed-bottom fabric comprising longitudinal strands, a continuous jointed cross linkage between the strands located approximately midway between the ends of the strands including links of two sorts arranged alternately, the links of one sort being flat plates including at each end a pair of spaced arms hooked around the strands, and the links of the other sort being helical springs hooked at their ends around the strands between the arms of the links of the first sort, and non-continuous cross linkage of the strands between said continuous cross linkage and the ends of the strands.

In witness whereof, I have hereunto set my hand.

REGINALD FERGUSON. 120
